UNITED STATES PATENT OFFICE.

ERLE K. BAKER, OF CHICAGO, ILLINOIS.

STARTING DEVICE FOR INTERNAL-COMBUSTION ENGINES.

1,016,314.

Specification of Letters Patent.

Patented Feb. 6, 1912.

Application filed February 8, 1910. Serial No. 542,703.

To all whom it may concern:

Be it known that I, ERLE K. BAKER, a citizen of the United States, residing at Chicago, in the county of Cook and State of Illinois, have invented certain new and useful Improvements in Starting Devices for Internal-Combustion Engines, of which the following is a specification.

This invention relates to novel and efficient means for starting internal combustion engines and particularly to such as make use of a number of cylinders.

The invention has for its object to enable the starting of such engines without the necessity of cranking them, or without the necessity of making use of other mechanical means, and without the necessity of using the inherent expansive qualities of gas stored under pressure.

The invention further relates particularly to automobile engines although it may be evident from a study of this specification and drawings that it is in no wise limited to such use.

In the drawings, Figure 1 shows a four cylinder automobile engine in elevation, looking toward that side of the same to which the inlet and exhaust pipes are connected, and showing the preferred form of my improved starting devices attached to the same, portions of the storage tanks being cut away; Fig. 2 is a plan view, showing the engine of Fig. 1 having attached to it the same devices as are shown in Fig. 1; Fig. 3 is a detail of the end portion of one of the storage tanks and the adjacent connections; Fig. 4 is a detail section of the explosion actuated compressor pump; and Fig. 5 is a detail of the preferred form of check valve for use in the supply pipes.

In the drawings, the engine 7 having cylinders 8, 9, 10, and 11, is provided with a carbureter, or other suitable mixer 12, supply pipes 13 and 14, and exhaust pipes 15, 16, 17, and 18 suitably connected to an outlet pipe 19.

The gas pump 20 has its suction pipe 21 connected to one of the supply pipes so that the pump will draw an explosive mixture which has been previously generated in the carbureter. The delivery pipe 22 from the pump is preferably connected to a manifold or other connection 23 whereby the storage tanks 24, 25, 26, and 27 will be supplied with gas from the pump. It is preferred that check valves be placed in the individual con-

nections to the tanks, and for that reason, the check valves 28, 29, 30, and 31 are provided. These will prevent a backward movement of gas from the storage tanks, thus insuring that the same will always be filled with the explosive mixture under pressure. The storage tanks are individually connected to the several cylinders by means of pipes 32, 33, 34, and 35, check valves 36, 37, 38, and 39 being placed in these pipes to prevent any back fire from the cylinders from communicating with the storage tanks.

The several pipes 32, 33, 34, and 35 are connected, respectively, to the explosion chambers of the cylinders through the means of valves 40, 41, 42, and 43 which latter may be connected together by means of a rod 44 which may be in communication with a suitable handle at the dash board so that the operator can open all of the valves simultaneously to permit explosive gas to enter all of the cylinder explosion chambers at the same time. When the operator has thus allowed the explosive gas to be admitted into all of the explosion chambers, it is evident that the application of a spark, or other igniting agency, to the engine will explode the charges in proper order, so as to insure that the engine will be started and the necessity of cranking it will be, thereby, eliminated.

As previously indicated, the check valves 36, 37, 38, and 39 serve to prevent the back fire from the cylinders from communicating with the inflammable mixture contained in the several storage tanks. These check valves further serve to maintain compression within the cylinders while the valves 40, 41, 42, and 43 are open. A relief valve 44^a may be placed in the main supply pipe 22 to prevent the accumulation of an excess pressure within the storage tanks, such as might be occasioned by too much pumping of the pump 20. A pressure gage 45 may be provided when this is desirable.

In Fig. 4, I show more in detail the preferred form of compressor. The lower portion of the pump is connected to the exhaust chamber of the engine 46 by means of a thimble 47, or in any other suitable manner. The numeral 48 indicates the exhaust valve of the engine. The body 49 of the compressor is provided with a neck 50, which is threaded onto the thimble 47 so that the passageway 51 is in direct communication with the exhaust chamber 46. A piston 52

2
working in the body portion of the compressor has connected to its upper end a compressor piston 53 which in turn works within a chamber 54. This last piston 53 is 5 preferably of smaller diameter than the piston 52 so that it will be possible, when desired, to secure a high degree of compression. A spring 55 surrounding the piston 53 tends to restore the same into lower position after each upward thrust on the piston 52. A suction pipe 21 connects with the compression chamber 54 through a check valve 56, and the discharge pipe 22 connects with the compression chamber through a 10 check valve 57.

The mode of operation of this explosion actuated compressor is as follows: The valve 40 being closed, the explosion pressure communicates through the passage 51 with the 15 lower face of the piston 52. This piston being forced upwardly carries with it the piston 53, thereby compressing the gas in the space 54, forcing the valve 56 to close, and expelling the charge of gas through the 20 valve 57 into the discharge pipe 22. The pressure within the chamber 46 being relieved by the opening of the valve 48 permits the piston 52 to be forced downwardly by the spring, thereby lowering the piston 25 53, closing the valve 57, and drawing a charge of gas into the space 54. Such operation of the compressor will attend each successive explosion occurring within the cylinder to which the compressor is attached.

In Fig. 3, I show more in detail the preferred connections to the end of each storage tank. In this case, the check valve 31 connects with a nipple 58, which nipple in 30 turn is connected onto one of the straight line connectors 59, and the other straight line connection of the same connecting through the medium of a nipple 60 with the corresponding tank, while the right-angle 35 connection connects to the cylinder supply pipe 32 through the medium of a union connection 61.

In Fig. 5, I show the preferred form of

check valve for use in the cylinder supply pipes. The same comprises a body portion 62 having a shoulder 63 against which a check ball 64 contacts. The chamber 65 is of sufficient size to allow the ball to enter it, and allow gas to pass up around the sides of the ball.

55 Although I have shown and described only one form of engine driven compressor, still it is evident that any form of compressor driven by the engine itself may be used for drawing explosive mixtures from the carburetor, or one of the associated connections, and delivering it to the storage tanks.

I claim:

1. In a mechanism for starting an internal combustion engine, a compressor adapted to be driven by the engine, the suction pipe of the compressor connected to the carburetor of the engine, a plurality of reservoirs for storing gas under pressure, a connection from the compressor to the reservoirs, a connection from each reservoir to a cylinder of the engine and a valve in each connection between the reservoir and the cylinder, substantially as described.

2. In a mechanism for starting an internal combustion engine, a compressor having its suction pipe suitably connected to the carburetor of the engine, a plurality of reservoirs for storing gas under pressure, and a connection from each reservoir to a cylinder of the engine, substantially as described.

3. In a mechanism for starting an internal combustion engine, a compressor adapted to be driven by the engine, and having its suction pipe suitably connected to the carburetor of the engine, a plurality of reservoirs for storing gas under pressure, a connection from the compressor to each reservoir, and a connection from each reservoir to a cylinder of the engine, substantially as described.

ERLE K. BAKER.
